US00D904123S

(12) United States Design Patent (10) Patent No.: US D904,123 S
(45) Date of Patent: * Dec. 8, 2020

(54) BOTTLE

- (71) Applicant: Shock Doctor, Inc., Fountain Valley, CA (US)
- (72) Inventors: Adam Peter Karl, IV, Burlington, VT (US); James Creath Frazier, Hinesburg, VT (US); Benjamin Casey Lanza, Sheldon, VT (US)
- (73) Assignee: Shock Doctor, Inc., Fountain Valley, CA (US)
- () Term: 15 Years
- (21) Appl. No.: 29/639,632
- (22) Filed: Mar. 7, 2018
